UNITED STATES PATENT OFFICE.

FRED MEYER, OF MALAD CITY, IDAHO.

SAND-PIPE CLEANER.

1,217,327.

Specification of Letters Patent. Patented Feb. 27, 1917.

Application filed July 6, 1916. Serial No. 107,846.

To all whom it may concern:

Be it known that I, FRED MEYER, a citizen of the United States, residing at Malad City, in the county of Oneida and State of Idaho, have invented certain new and useful Improvements in Sand-Pipe Cleaners, of which the following is a specification.

This invention relates to sand pipe cleaners, and more particularly to means for 10 cleaning the sand pipes of a steam locomotive.

One of the main objects of the invention is to provide a device of the character stated of simple construction and operation which 15 may be easily applied to any locomotive of standard construction. A further object is to provide a device so arranged as to effectually prevent freezing of the sand pipes. Further objects will appear from the de- 20 tailed description.

In the drawings:—

Figure 1 is a side view of a conventionally formed locomotive with the invention applied, and

25 Fig. 2 is a section on line 2—2 of Fig. 1.

The locomotive 1 is provided with the usual sand box 2, steam dome 3, and drivers 4. The sand pipes 5 are connected at their upper ends to opposite sides of the sand box 30 and project downwardly and rearwardly with their lower ends slightly in advance of the forward driver 4. For supporting these pipes I provide brackets 6 secured to the main frame of the locomotive and secure 35 the pipes to the same. In each sand pipe I mount a gate valve 7, near the upper end thereof. The stem 8 of this valve is connected by a link 9 to an arm 10, the inner end of which is pivoted to the lower end of 40 an arm 11. The upper end of arm 11 is keyed on the end of a transverse rock shaft 12 mounted in bearing eyes 13 secured in the sand box. Collars 14 are secured on the shaft 12 adjacent the eyes 13 and prevent 45 longitudinal movement of the same. A pull rod 15 is pivotally connected at its forward end to the upper end of an arm 16 keyed to rock shaft 12. This pull rod projects into the cab 17 of the locomotive within easy 50 reach of the engineer. It will be evident that, by operating rod 15, the gate valves 7 may be opened or closed as desired.

I provide each of the pipes 5, with a downwardly directed angularly disposed nipple 18 at a point below the valve 7. In 55 each nipple I secure an end of a branch pipe

19 which is connected to a main pipe 20. This main pipe communicates with the interior of steam dome 3, at the top thereof, and is provided with a valve 21 at its inner 60 end which is operated by a rod 22 projecting into the cab 17 within reach of the engineer.

In the event of the sand pipe 5 becoming stopped, from freezing, which often happens in moist, cold climates, the same may be quickly opened or cleaned by admitting steam through the pipes 19. To clean the pipes 5, the gate valves 7 are first closed, then the rod 22 is operated to open the valve 21. This admits steam into pipe 20 and from this pipe into the branch pipes 19. The steam enters the sand pipes below the valves and flows through the same heating them and thawing out any frozen sand which may 75 be stuck in the pipes. This quickly cleans the pipes so that, when the valves 7 are again opened, after shutting off the steam, the sand will readily flow from the box 2 on to the rail in front of the drive wheel. 80 By taking the steam from the top of the dome 3, I insure that the steam supplied to the pipe 5 will be perfectly dry thus avoiding all danger of dampness such as would tend to cause freezing of the pipes. 85 In addition to forming a means for cleaning the pipes, my invention also provides a means for indicating whether the pipes are stopped or not. By closing the valves 7 and opening the valve 21 the steam will flow 90 from dome 3 through the pipes 5 and out of the lower ends thereof. If no steam comes from the lower ends of the pipes this indicates that the pipes are stopped and need cleaning. On the other hand, if the steam 95 flows readily and easily from the pipes it is an indication that the pipes do not need cleaning.

As will be noted, the gate valves 7 are mounted exterior of the sand box and remote from the same. The nipples 18 are directed downwardly and are below the gate valves, being thus spaced a considerable distance from the sand box. By this construction, my apparatus is well adapted for use 100 in connection with a sand box of standard construction, no changes in construction of the box being necessary. Also, as the discharge ends of the steam pipes are below 105 the gate valves and remote from the sand box, all danger of any water of condensation resulting from the steam discharge get- 110

ting into the sand and so as to cause freez-~~ing~~ In this case, by loosening the lower union 20
ing of the same is eliminated.

By my invention I provide a simple and 25
efficient means for determining whether the
5 sand pipes of a locomotive are stopped or
not, and also for cleaning the pipes if they
are stopped.

I mount the valve 7 and nipple 18 for
each sand pipe in a separate section 5^a of
10 pipe which is connected in the pipe 5 by
means of unions 5^b. By this means, if it at
any time becomes necessary to remove the
lower section of the pipe, or to remove the
15 valve 7 or nipple 18, this can be readily and
easily accomplished by unscrewing the
unions 5^b. This is of special importance in
the event of the lower portion of the pipe 5
becoming bent, or being broken off, through
contact with some obstruction on the track.

~~5^b~~ the bent or broken section of pipe can be
quickly and easily removed and a new sec-
tion inserted.

What I claim, is:

In track sanding means, the combination 25
of a sand box, sand pipes communicating
with said box, gate valves mounted in each
of said pipes exterior of the sand box, and
downwardly directed steam pipes communi-
30 cating with each of said pipes below said
gate valves and remote from the sand box.

In testimony whereof I affix my signature
in presence of two witnesses.

FRED MEYER.
